UNITED STATES PATENT OFFICE

90,592

DESIGN FOR A STICK OF CHEWING GUM

Conrad E. Peterson, Malden, Mass.

Application December 22, 1932. Serial No. 46,562

Term of patent 3½ years

To all whom it may concern:

Be it known that I, CONRAD E. PETERSON, a citizen of the United States, residing at Malden, Middlesex County, State of Massachusetts, have invented a new, original, and ornamental Design for a Stick of Chewing Gum, of which the following is a specification, reference being had to the accompanying drawing, forming a part thereof.

The single figure of the accompanying drawing is a perspective view illustrating a stick of gum embodying my design.

I claim:

The ornamental design for a stick of chewing gum, substantially as shown.

CONRAD E. PETERSON.
